UNITED STATES PATENT OFFICE.

CLARENCE S. SNAVELY, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

SIGNAL.

1,154,068.

Specification of Letters Patent. Patented Sept. 21, 1915.

Application filed May 2, 1914. Serial No. 835,868.

To all whom it may concern:

Be it known that I, CLARENCE S. SNAVELY, a citizen of the United States, residing at Edgewood Borough, in the county of Allegheny and State of Pennsylvania, have invented certain new and useful Improvements in Signals, of which the following is a specification.

My invention relates to signals, and particularly to railway signals of the type in which sources of light are employed for giving indications.

I will describe one form of signal embodying my invention and will then point out the novel features thereof in claims.

In the accompanying drawings, Figure 1 is a view, partly diagrammatic, showing one form of signal embodying my invention, and showing also a portion of a railway track along which the beam of light from the signal is projected. Fig. 2 is a view showing a reflector comprised in the signal shown in Fig. 1.

Referring to Fig. 1, S designates a signal comprising a source of light L, here shown as being an incandescent electric lamp, and a lens 2 for projecting light from the lamp along the railway track R.

The signal S must be located far enough above the track R to be clear of cars and trains, and is preferably slightly inclined, as shown, so that the axis 6 of the lens 2 will intersect the track at about the point farthest from the signal at which it is desirable that the indication given by the signal shall be clearly distinguishable.

The signal here shown is adapted for use both in daylight and at night, and in order to give indications at long range in daylight without requiring excessive power, the signal is so constructed that the direct rays from the lamp L which strike the lens 2 are projected therefrom in a beam having only a few degrees divergence, thus producing a slender beam of high candle-power. The upper and lower limits of this beam may be represented by lines 4 and 4^a. It will be seen, therefore, that as an observer proceeds along the track toward the signal from the point 7, this slender beam 4-4^a will be visible until he reaches a point 8 at which the lower limit 4^a of the beam intersects the track, and that unless other means are provided the light from the signal will be invisible at all

locations between point 8 and the signal. In actual practice, when the signal is designed to give indications in daylight as well as at night, the distance between point 8 and the signal is from one hundred to three hundred feet. It is desirable, however, that the light from the signal should be visible at all locations between the point 8 and a point nearly beneath the signal, and to accomplish a continuous indication between these points requires a source of light extending from a point near the lamp L to the upper edge of the lens 2. To produce such a source of light I provide a reflector 3 having an opaque, rough, unpolished surface, such for example as a sheet of metal having a surface of unglazed enamel, this reflector being located just outside of the cone whose base is the lens 2 and whose apex is in the lamp L. This reflector diffuses the light from the lamp L and reflects the diffused rays toward the lens 2, by which they are projected in a beam whose limits are approximately defined by lines 5 and 5^a. Owing to the diffusion of the light by the reflector 3, the lens 2 appears to be fully illuminated from all locations on the track between points 8 and 9, and the light is of substantially the same intensity at all locations between these points.

Owing to the fact that the reflector 3 is not polished and therefore diffuses all light which strikes it, this reflector will not cause the signal to falsely appear illuminated when rays of light from an outside source, such as from a locomotive headlight, enter the lens 2.

It will be seen that the reflector 3 does not interfere with the rays of light which pass directly from the lamp to the lens but that it collects a portion of the light which would otherwise be wasted, and reflects it toward the lens from which this light is projected to the track between points 10 and 9.

The results secured by a reflector of the kind described cannot be attained by the use of a polished reflector, because the latter would reflect the light in more intense beams at fewer angles, thus giving a beam of smaller spread, and would cause a few bright spots on the lens at several points of observation. Furthermore, a polished reflector would be apt to cause the signal to falsely appear illuminated when rays from an outside source of light strike the lens.

Having thus described my invention, what I claim is:

1. A signal comprising a source of light, a lens for projecting direct rays from said source for indicating at long range, and a plane reflector located at an angle to said lens and having a light diffusing surface for projecting rays from said source toward said lens for indications at short range.
- 10 2. A signal comprising a source of light, a lens for projecting direct rays from said

source for indicating at long range, and a reflector located at an angle to said lens and having a light diffusing surface for projecting light from said source toward said lens for indicating at short range.

In testimony whereof I affix my signature in presence of two witnesses.

CLARENCE S. SNAVELY.
